UNITED STATES PATENT OFFICE.

MICHAEL WOICULA, OF WILMINGTON, DELAWARE.

DESIGN FOR A COMBINATION IMPLEMENT.

48,539.

Specification for Design.

Patented Feb. 8, 1916.

Application filed November 8, 1915. Serial No. 60,439. Term of patent 7 years.

To all whom it may concern:

Be it known that I, MICHAEL WOICULA, a subject of the Czar of Russia, residing at Wilmington, in the county of New Castle and State of Delaware, have invented a new, original, and ornamental Design for a Combination Implement, of which the following is a specification, reference being had to the accompanying drawing, forming part thereof.

The figure is a view in front elevation of a combination implement, showing my new design.

I claim:—

The ornamental design for a combination implement, as shown.

MICHAEL WOICULA.
